UNITED STATES PATENT OFFICE

HOWARD C. LESLIE, OF MILTON, MASSACHUSETTS, ASSIGNOR TO B R E MANUFACTURING CO., OF HYDE PARK, MASSACHUSETTS, A CORPORATION OF MASSACHUSETTS

HINGE CONNECTION FOR WATER CLOSET SEATS AND COVERS

Application filed October 9, 1931. Serial No. 567,833.

This invention relates to hinge connections for members to be pivotally connected to other members and is particularly adapted in mounting seats and covers therefor on water closet hoppers.

The invention consists of novel means for attaching the hinge plates to the seats and covers, the object being to rigidly secure these plates in position without the use of 10 screws or similar elements.

This object is attained by the mechanism shown in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged 15 and organized, and the invention is not limited to the precise arrangement and organization of these instrumentalities as herein shown and described except as required by the scope of the appended claims.

25 Of the drawings

Figure 1 represents a plan of a water closet hopper having cover and seat attached thereto by hinge connections embodying the principles of the present invention.

30 Figure 2 represents a side elevation of same.

Figure 3 represents a rear elevation of same drawn to an enlarged scale with portions thereof in section.

35 Figure 4 represents a side elevation of one of the hinge connections and its support and showing the cover closed.

Figure 5 represents a side elevation of same with the cover raised.

40 Figure 6 represents a section on line 6, 6, on Fig. 4.

Figure 7 represents a section on line 7, 7, on Fig. 4.

45 Figure 8 represents an elevation of one of the hinge members showing the inner face thereof.

Figure 9 represents a side elevation of the support for said hinge member.

50 Figure 10 represents a section through a portion of the seat and showing means

for securing an insulated trunnion thereon.

Figure 11 represents a vertical transverse section of a two-part seat with trunnions secured thereto by a tubular member.

Figure 12 represents a horizontal transverse section showing means for mounting the two-part seat upon the supports without a cover.

Figure 13 represents a vertical transverse section of a one-part seat and cover showing 60 the end plates provided with hubs extending into sockets in the seat.

Figure 14 represents an elevation of the inner face of an end plate provided with a seat engaging stud, and

Figure 15 represents an elevation of the inner face of an end plate used in connection with the seat when no cover is used.

Similar characters indicate like parts throughout the several figures of the drawings.

In the drawings, 10 is a portion of a water closet hopper having a flange 11 to which posts 12 are secured in the usual manner by nuts 13 threaded to shanks 14 extending 75 through the flange 11.

The upper end of each post 12 is preferably curved forwardly and is provided at its upper end with an opening 15 into which extends a cylindrical hub 16 formed upon an end plate 17, each hub being provided with a cylindrical socket 16a at its inner end.

The hubs 16 of the end plates 17 are prevented from being displaced from the supports 12 by means to be hereinafter described.

The upper end of each plate 17 has a forward extension 18 and on the inner face of each member 17 and extension 18 are two cylindrical lugs 19 which are adapted to extend into cylindrical holes formed in a rearward extension 20 forming part of a cover 21.

Each end plate 17 is provided on its inner face with a semi-annular rib 22, the lower end of which is adapted to abut the forward side of one of the posts 12 when the cover is in horizontal position, as shown in Fig. 4, while the opposite end of said rib 22 is 100

adapted to abut the rear of said post 12 when the cover 21 is in raised position, as indicated in Fig. 5.

In each socket 16 α is a collar 17 α surrounding the outer end of a cylindrical metal rod 23 which accurately fits a cylindrical hole 23 α extending transversely of a rearward extension 24, forming a portion of a two-part seat 25, open at the front and 10 rear, as shown in Figs. 1 and 3.

The distances between the outer side faces of the extensions 24 is less than the distance between the outer side faces of the extension 20, so that in looking down upon the 15 top of the seat 21 the extensions 24 are not exposed to view.

Between the two extensions 24 is a tubular member 26 of insulating material which retains the two extensions 24 properly 20 spaced apart.

Between these two extensions 24 and in front of the tubular member 26 is a tube 27 of the same length as tubular member 26 and through which extends a metal rod 28, 25 the opposite ends of which are tapered and provided with right hand threads as at 29.

The inner ends of the metal rods 23 are tapered, as at 30, and in contact before these rods are forced towards each other, while 30 their outer ends are upset over the outer ends of the collars 17 α which serve as trunnions for the seat 25.

The holes 23 α serve as guides for the rods 23 so that the tapered ends of these rods 35 will always meet accurately within the tubular member 26, substantially midway of its length.

The holes 23 α are first formed in the extensions 24 and then the rods 23 with the 40 collars or trunnions 17 α mounted on the outer ends thereof are forced into these holes 23 α under pressure.

At the same time that these rods 23 are being forced inwardly with their tapered 45 ends 30 contacting, an electric current is passed through the rods 23 causing said inner ends 30 thereof to be welded together so that the trunnions 17 α are permanently secured in position and cannot be separated 50 from said seat 25.

Preferably a washer 30 α is positioned between each trunnion 17 α and the outer side wall of extension 24 to prevent said side wall from contacting with any portion of the end 55 plate 17 or support 12.

The threaded ends 29 of the rod 28 are so positioned in the extensions 24 of the seat that the inner faces of the extensions 24 will bear firmly against the opposite ends of the 60 tube 27.

When the metal rods 23 have been welded together with the inner walls of the extensions 24 bearing against the opposite ends of the tubular member 26, the separation of 65 said extensions will be effectually prevented

and the trunnions 17 α will be rigidly held against the washers 30 α so that they cannot turn relatively to the rods 23.

When this has been accomplished the two parts of the seat 25 are rigidly held together and cannot spread apart, move inwardly or assume inclined positions relatively to each other.

When the inner ends of the rods 23 are thus connected together, it is impossible for 70 the cylindrical trunnions 17 α forming a pivot for the seat 25 to be displaced.

One set of lugs 19 oppositely disposed on the end plates 17 have metal rods 19 α extending inwardly therefrom into a hole extending transversely of the extension 20 of the cover 21.

The inner ends of these rods 19 α are tapered and in contact before pressure is applied to force them toward each other.

When such pressure is applied and an electric current is passed therethrough, the tapered ends will be welded together so that it is impossible to separate them and consequently the hubs 16 of the end plates 17 cannot become dislodged from the cylindrical bearings 15 in the supports 12.

The hubs 16 form the pivot for the cover 21 to turn on and the trunnions 17 α form the pivot for the seat 25 to turn on.

It will be noted that the axes of the trunnions 17 α and hubs 16 are coincident so that when the seat 25 and cover 21 are both raised there can be no movement of one relatively to the other and consequently all chafing is avoided which is a great advantage as such chafing will mar the material enveloping the seat 25 and cover 21 and make them unsightly.

There are two distinct operations of welding in the assembling of the seat 25 and cover 21 on the supports 12, the first being the welding together of the rods 23 to secure the trunnions 17 α to the seat and the next being to secure the end plates 17 in position by welding together the rods 19 α in the cover 21.

To prevent short circuiting in the rods 23 when the rods 19 α are being welded together one of the trunnions 17 α is surrounded by a collar 31 of insulating material and preferably a paper disk 32 is placed between the trunnion 17 α and the washer 30 α , as indicated in Fig. 10.

To further insure against short circuiting it is desirable to have an air space 33 between the outer end of the trunnions 17 α and the inner ends of the sockets 16 α as shown in Fig. 7.

By this construction the use of screws and similar instrumentalities is dispensed with and the outer faces of the end plates 17 are smooth and unbroken, thus leaving no depressions in which foreign substances may lodge.

As before stated, the rearward movement of the cover 21 when in its raised position is limited by the rearward end of the ribs 22 coming into contact with the posts 12.

5 By this construction of hinge connection, said hinge connections may be secured to the cover 21 or seat 25 or to both the cover 21 and seat 25 after said cover 21 and seat 25 have been enveloped with sheets of celluloid or other material without any danger of injury thereto.

10 In some cases, it is desirable to dispense with the cover 21 and pivot the two-part seat 25 directly upon the posts 12, in which case the upward extensions 18 of the end plates 17 are dispensed with, and an end plate 34 is used, such for instance as that shown in Fig. 15, in which case the rods 23 are secured directly to the hubs 34x of said end plates 20 34 and lugs 35 are provided which extend into the seat 25.

This construction is shown in Fig. 12.

15 In this particular construction just described the hubs 34x extend into the openings 15 in the posts 12 and each plate 34 is provided with stop shoulders 22x to coact with posts 12 to limit the movement of the seat in either direction.

20 In some cases headed collars 36 are disposed in the outer face of the extensions 24 as shown in Fig. 13, the outer ends of these collars extending slightly beyond the outer faces of the extensions 24 into contact with the inner faces of the supports 12, thereby leaving a slight space between the inner faces of the posts 12 and the outer faces of the extensions 24.

25 In this construction the end plates 17 are secured in position by welding together the rods 19x in the cover and said end plates 17 have studs 37 extending therefrom through the posts 12 and into the collars 36.

30 In the several constructions shown and described, all rubbing against the outer face 40 of the extension 24 is obviated when the seat 25 is raised or lowered.

35 This is of some consequence as the seat is usually covered with celluloid or similar material and if chafed becomes unsightly.

40 In some cases the trunnions 17x may be secured to the seat by a hollow rod 38 extending through seat 25 and trunnions 17x and upset at its opposite ends, as shown in Fig. 11.

45 By mounting the seat and cover on a water closet hopper by such hinge connections as herein shown and described, a perfectly sanitary construction is provided which has great strength and the elements are permanently retained in position.

50 By this construction the use of all screws and similar instrumentalities is entirely dispensed with which is a considerable advantage, as such elements are liable to become 60 loose in use and permit the various elements

of the hinge connections to get out of commission.

The construction herein shown and described is particularly adapted for use in connection with seats which are formed in two parts separated both at the front and rear.

75 The stop rib 22 surrounds and is slightly separated from the periphery of the semi-annual ends 39 of the posts 12.

The end plates 17 with the rib 22 hide from view the greater part of the posts 12 when the cover 21 is either in raised or lowered position.

80 It is believed that the operation and many advantages of the invention will be understood without further description.

Having thus described my invention, I claim:

1. In a device of the class described, a 85 two-part seat having alined holes at the rear end thereof; a tubular member between the two parts of said seat and in alinement with said holes; trunnions at the outer ends of said holes; and two rods secured to and extending from said trunnions disposed in and fitting said holes and tubular member with their inner ends in contact and permanently joined together within said tubular member.

90 2. In a device of the class described, a 95 two-part seat having alined holes at the rear end thereof; a tubular member between the two parts of said seat and in alinement with said holes; metal plates at the outer ends of said holes each provided with a 100 member extending therefrom disposed in and fitting said holes and tubular member with the inner ends of said projections in contact and permanently joined together within said tubular member, each plate having a short projection extending into an outer wall of said seat; and a connecting member for the two parts of said seat parallel to and in front of said projections and spaced therefrom.

105 3. In a device of the class described, a 110 seat having a hole extending transversely of its rear end; supports adjacent the opposite side faces of said rear end and having cylindrical openings in the upper ends thereof; metal end plates having on their inner faces hubs fittings said openings; and projections extending from said plates disposed in said hole with their inner ends in contact and permanently joined together.

115 4. In a device of the class described, a 120 seat having a hole extending transversely of its rear end; supports adjacent the opposite side faces of said rear end and having cylindrical openings in the upper ends thereof; metal end plates having on their inner faces hubs fitting said openings and provided with sockets in the inner ends thereof; trunnions for said seat disposed in said sockets; and projections extending from 130

said trunnions disposed in said hole with their inner ends in contact and permanently joined together; and a cover permanently secured to the upper ends of said end plates.

5. In a device of the class described, a seat; a cover; two supports; an end plate pivotally mounted on each support and permanently secured to said cover, said end plates having alined sockets; and trunnions in said sockets having projections therefrom extending through said seat, the inner ends of said projections being in contact and permanently connected together.

6. In a device of the class described, a seat having a rear extension with a transverse hole therein; trunnions at the outer ends of said holes each provided with a projection disposed in and fitting said holes with the inner ends of said projections in contact and permanently joined together; end plates having hubs provided with sockets to receive said trunnions; a cover having a rear extension permanently secured to and movable with said end plates; and fixed bearings for said hubs.

7. In a device of the class described, a seat having a rear extension; alined trunnions on the opposite side walls of said extension; supporting posts; insulating means surrounding one of said trunnions; metal end plates pivotally mounted on said posts and having alined sockets to receive said seat trunnions; a cover having a hole extending transversely thereof; projections from said end plates disposed in and fitting the hole in said cover with the inner ends of said projections in contact and permanently joined together.

8. In a device of the class described, a two-part seat open at front and rear and having rear extensions; separating means between the two parts of said seat; trunnions extending from the opposite side walls of said extension; end plates provided with sockets to receive said trunnions; supports on which said end plates are pivotally mounted; a cover; and means projecting inwardly from each end plate into said cover and permanently joined together.

9. In a device of the class described, a two-part seat having rear extensions with alined transverse holes therein; a tubular member between the two parts of said seat and in alinement with said holes; metal end plates at the outer ends of said holes each provided with a projection disposed in and fitting said holes and tubular member with the inner ends of said projections in contact and welded together; a tube in front of and parallel to said tubular member; and a rod extending through said tube with its opposite ends threaded to said seat parts.

10. In a device of the class described, a seat having a rear extension provided with a hole extending transversely thereof; sup-

ports adjacent the opposite side faces of said rear extension and having cylindrical openings in the upper ends thereof; metal end plates having on their inner faces hubs fitting said openings, said hubs having alined sockets therein; trunnions at the opposite sides of said seat extension and disposed in said sockets; projections extending from said trunnions disposed in said hole with their inner ends in contact and permanently joined together; a cover; projections from the upper ends of said end plates extending into a transverse hole in the rear end of said cover with their inner ends permanently secured together; and means on the inner faces of said plates surrounding and slightly separated from the cylindrical upper ends of said supports and coacting with said supports to limit the movement of said cover in either direction.

11. In a device of the class described, two fixed supports having alined openings in the upper ends thereof; end plates having cylindrical hubs disposed in said openings, said hubs having alined sockets therein; a cover having a transverse hole in its rear end; rods extending from said end plates disposed in and fitting said hole with their inner ends in contact and permanently joined together; a seat having a rear extension between said supports; and trunnions at the opposite sides of said extensions disposed within said sockets.

Signed by me at 746 Old South Bldg., Boston, Massachusetts, this 30th day of September, 1931.

HOWARD C. LESLIE.
